UNITED STATES PATENT OFFICE.

JAMES L. CARDER, OF LOS ANGELES, CALIFORNIA, ASSIGNOR OF ONE-THIRD TO
JOHN A. STREET, OF LOS ANGELES, CALIFORNIA.

OIL-WELL CLEANER.

Application filed June 2, 1924. Serial No. 717,268.

To all whom it may concern:

Be it known that I, JAMES L. CARDER, a citizen of the United States, and resident of Los Angeles, in the county of Los Angeles, State of California, have invented new and useful Improvements in an Oil-Well Cleaner, of which the following is a specification.

This invention relates to a device for cleaning operating oil wells and the like. In the operation of oil wells the interstices in the oil bearing strata often become clogged with deposits of bituminous and like substances, thereby hindering the flow of oil. This also occurs in the perforated and screen pipes commonly used. The removal of this clogging matter will increase the output of the well. A hot fluid such as water may be employed to liquefy and make more fluent the deposited material and to wash the same from the pipes and strata. In the employment of fluids for this purpose, a means to provide circulatory passages for the fluid and to confine the latter under desired pressures to desired locations and zones is a desideratum.

The primary object of this invention is to provide a cleaning device which may be lowered freely into a well hole and has packing means expandable at will to confine the flow of cleaning fluid to a selected location. Another object of this invention is to provide a novel expandible packing and means for operating the same. In addition to the broader objects of this invention, there are certain details of structure.

These objects together with other objects and corresponding accomplishments are obtained by means of the embodiments of my invention illustrated in the accompanying drawing, in which:

Fig. 1 is a vertical section through a cleaner having two packers; Fig. 2 is an elevation of a similar cleaner having one packer; Fig. 3 is a perspective view of the plunger valve; Fig. 4 is a development of a fragment of the packing fabric; Fig. 4^a is a section as seen on the line 4^a of Fig. 4; Fig. 5 is a vertical sectional view of another species of cleaner; Fig. 6 is a fragmentary section as seen on the line 6-6 of Fig. 1; Fig. 7 is a section as seen on the line 7-7 of Fig. 1 and Fig. 8 is a section as seen on the line 8-8 of Fig. 6 on an enlarged scale.

Referring more particularly to the struc-

ture shown in the figures exclusive of Fig. 5, a service pipe shown in dotted lines in Fig. 1 and indicated by 10 is connected to a tubular member 11. Secured to the member 11 is a cage 12 to the bottom of which is connected a tubular body 13. A coupling collar 14 is secured to the bottom of the tubular body and secured thereto are other depending portions of the structure. A split clamp ring 15 is mounted about the collar 14 and binds a packing thereto. This packing consists of an envelope or shell of tubular form enclosing the body. Referring to Figs. 4 and 4^a, it is shown as formed of a flexible material 16 such as canvas and has inserts 17 spaced from one another and extending the length thereof. These inserts are of leaf form and of spring metal. The shell is pleated so that it may be expanded and contracted. The central portion may be reinforced by a pleated fabric 18 secured to the fabric 16. Eyelets 19 extend through the fabric 16 at the ends so as to secure the pleats together. They also provide openings through which screws may be inserted to secure the packing to the collars 14 and 20. Collar 20 is slideable upon the body 13, and the packing is secured thereto by means of a clamp ring 21. The body is provided at the collar 20 with diametrically opposite longitudinally extending slots, through which a cross pin 22 extends. Thus, when collar 20 is moved downwardly upon the body, the springs in the packing are bowed outwardly to belly out the shell and expand the latter. Means are provided for moving the collar.

A means for operating the packing is shown disposed within the cage 12, see Figs. 1 and 6. This means comprises a plunger valve having a cylindrical body 23. The body may be hollow and has upstanding therefrom guide arms 24. Depending from the body are arms 25, which act as guide arms and also support the cross pin 22, thereby tying the plunger valve to the packing. The length of the body 23 is such that it may be disposed within the cage 12 in the manner shown in Fig. 6, permitting fluid to pass around the plunger body from the tubing 11 to the tubular body 13. In this position, the packing is expanded, the collar 20 being in its lower position. When the packing is collapsed, the plunger is disposed in the tubing 11 above the cage 12 so as to occlude the flow of fluid to the body.

Referring more particularly to Fig. 2, a perforated pipe 26 is shown connected to the tubular body 13 by means of the coupling collar 14. Mounted upon the end of the perforated tube 26 is a cap 27 having a number of perforations, preferably slanted to give a rotary tangential movement to the water or fluid discharge from the cleaner. The cleaner is operated in the following manner:

The pump tubing is removed, the cleaner, as shown in Fig. 2, secured to the bottom of a string of service pipe and lowered into the hole. When the desired position has been reached, the flushing fluid, such as hot water, is introduced under the desired pressure into the service pipe. The pressure upon the top of the plunger valve 23 moves the latter downwardly into the cage 12, causing the expansion of the packing as shown in Fig. 6. The flushing fluid then passes outwardly through the perforations in the pipe 26 below the packing and cleans the perforations or screens in the oil pipe below the packing, passing outwardly and then upwardly toward the surface. The hot flushing fluid also washes the exposed surfaces of the strata, and may penetrate the same. When the pressure is removed from the service string, the springs 17 straighten holding the fabric 16 in pleats and moving the plunger valve into its upper position. The cleaner can then be elevated by means of the service pipe.

It may be wished to confine the fluid within the casing to a given location between two spaced packers. The structure shown in Fig. 1 will accomplish this purpose. The perforated tube 26 has a coupling collar 28 secured thereto, to which is connected a tubular body 29. At the bottom of the body 29 is a collar 30, to which is clamped by means of a ring 31 a packing 32 of the same character as that before described. Closing the bottom of the collar is a plug 33. Slidably mounted upon the body 29 is a sleeve 34. The packing 32 is clamped to the sleeve 34 by means of a ring 35. Extending diametrically across the sleeve 34 and disposed in longitudinally extending slots in the body is a pin 36. The construction of the packer just described is substantially the same as the upper packer. A tie rod 37 connects pins 22 and 36 so that upon movement of the plunger valve 23 downwardly, both packers are expanded, thereby confining the flushing fluid to the space between the packings.

In Fig. 5, a structure is shown having a packer operable by a line extending to the surface so as to be actuated by the operator. A fitting 38 is closed at the top by a plug 39 bored for the passage of a line and equipped with a stuffing box 40. A service pipe 41 is connected to one branch and extends to

a means for supplying flushing fluid. Secured to the fitting is a section of tubing 42. A coupling collar 43 connects tubing 42 to a tubular body 44, and a perforated pipe 45 is secured to the body 44 by means of a collar 46. Pipe 45 has a cap 47 closing the bottom thereof and of the same character as the cap 27 shown in Fig. 2. The body 44 is longitudinally slotted for the passage of a cross pin. A clamp ring 48 secures an expansible packing 49 to collar 43, the packing being of the same character as disclosed in the structure shown in Figs. 1 and 2. Mounted upon the body 44 is a slidably collar 50 to which the lower edge of the packing is secured by means of a clamp ring 51. Extending diametrically across the collar 50 is a pin 52. A cable or line 53 is secured to the cross pin and extends upwardly through the plug 39 and stuffing box. 85

The cleaner is lowered into the hole, after the removal of any working parts within the casing, this being done by means of the service string 41. When the cleaner has reached the desired location, the cable 53 is 90 operated to lift the collar 50 and thereby expand the packing. The cable is then anchored or fixed to hold the packing in expanded position. When it is desired to remove the cleaner, the tension upon cable 95 53 is released, allowing the springs in the fabric 49 to collapse the packing.

What I claim is:

1. A device of the character described comprising the combination of a hollow body; a collapsible packing having a shell of flexible material disposed about said body, and longitudinally extending springs within said shell; and means to longitudinally contract said shell so as to bow said springs 100 and expand said packing. 105

2. A device as specified in claim 1 characterized by the shell being pleated and adjacent pleats being secured to each other at their ends. 110

3. A device of the character described comprising the combination of a service conduit, a hollow body secured thereto provided with a discharge section; a collapsible packing having a shell of flexible material disposed about said body and longitudinally extending springs within said shell; and means operable at will to bow said springs and expand said packing. 115

4. A device as specified in claim 3 characterized by the shell being pleated and adjacent pleats being secured to each other at their ends. 120

5. A device of the character described comprising the combination of a hollow body; a collapsible packing having a shell of flexible material disposed about and secured to said body at one end, longitudinally extending springs within said shell, a slid- 125 able member on said body secured to the 130

other end of said shell; and means secured to said slidable body to longitudinally contract said shell so as to bow said springs and expand said packing.

5 6. A device as specified in claim 5 characterized by the shell being pleated and adjacent pleats being secured to each other at the ends.

7. A device of the character described comprising the combination of a service conduit, a hollow body secured thereto provided with a discharge section; a collapsible packing having a shell of flexible material disposed about and secured to said body at one end, longitudinally extending springs within said shell, a slidable member on said body secured to the other end of said shell; and means secured to said slidable body to longitudinally contract said shell so as to bow said springs, and expand said packing.

8. A device as specified in claim 7 characterized by the shell being pleated and adjacent pleats secured to each other at their ends.

25 9. A device of the character described comprising the combination of a service conduit, a hollow body connected thereto provided with a discharge section; a collapsible packing having a shell of flexible material disposed about and secured to said body at one end, longitudinally extending springs within said shell, a slidable member on said

body secured to said shell at the other end; a plunger valve secured to said slidable member to close the passage way to said body 35 when said shell is collapsed and to longitudinally contract said shell and open said passage-way so as to bow said springs and expand said packing.

10. A device as specified in claim 9 characterized by the shell being pleated and adjacent pleats being secured to each other at their ends.

11. A device of the character described, comprising the combination of a service conduit, hollow bodies provided with an intermediate discharge section connected to said conduit; collapsible packings having shells of flexible material, each shell being disposed about and secured to a body at one end, longitudinally extending springs within said shells, slidable members on said bodies each secured to a shell at its free end; and means securing said slidable members together and operable at will to bow said 55 springs and expand said packings.

12. A device as specified in claim 11 characterized by the shell being pleated and adjacent pleats being secured to each other at their ends.

In witness that I claim the foregoing I have hereunto subscribed my name this 28th day of May, 1924.

JAMES L. CARDER.
